CLAIM

The ornamental design for the decorative reflector for
low-voltage, outdoor accent lights, as shown and de-
scribed.

DESCRIPTION

FIG. 1 is a rear elevational view of a decorative reflec-
tor for low-voltage, outdoor accent lights showing our
new design;

FIG. 2 is a top plan view thereof;

FIG. 3 is a front elevational view thereof;

FIG. 4 is a side elevational view thereof, the opposite
side being a mirror image;

FIG. 5 is a top, front perspective view thereof.

The light shown in broken lines in FIG. 4 is for illustra-
tive purposes only.

FIG. 1

FIG. 2

FIG. 5

FIG. 3
